UNITED STATES PATENT OFFICE

MICHAEL W. McARDLE, OF CHICAGO, ILLINOIS

DESIGN FOR A COMBINED LIGHTER AND TRAY

Application filed September 17, 1929. Serial No. 32,778. Term of patent 7 years.

To all whom it may concern:

Be it known that I, MICHAEL W. McARDLE, a citizen of the United States, residing at Chicago, in the county of Cook and State of Illinois, have invented a new, original, and ornamental Design for a Combined Lighter and Tray, of which the following is a specification, reference being had to the accompanying drawing, forming part thereof.

In the drawing—

The figure is a perspective view of a combined lighter and tray showing my new design.

I claim:

The ornamental design for a combined lighter and tray, as shown.

MICHAEL W. McARDLE.
